UNITED STATES PATENT OFFICE.

HENRY KIELBERG, OF MARTINS FERRY, OHIO, ASSIGNOR TO WHITAKER-GLESSNER COMPANY, A CORPORATION OF WEST VIRGINIA.

SHEET-METAL RECEPTACLE.

Application filed December 17, 1921. Serial No. 522,989.

To all whom it may concern:

Be it known that I, HENRY KIELBERG, a citizen of the United States of America, and resident of Martins Ferry, county of Belmont, and State of Ohio, have invented certain new and useful Improvements in Sheet-Metal Receptacles, of which the following is a specification.

This invention relates broadly to sheet-metal receptacles, and it has for its primary object to provide a corrugated metal receptacle of the general character or type commonly employed as ash cans, garbage cans and the like, which has a tapered form, rendering it readily nestable for shipping and storage purposes.

A further object is to provide a tapered can having its body corrugated for stiffening purposes, the corrugations thereof being gradually increased in depth from its upper end to its lower end to provide for absorption of the surplus metal presented as a natural consequence of the gradual reduction of the diameter of the can.

A still further object is to provide a can body of the character mentioned having the surplus or excess metal of the various corrugations laid over in substantially flat folds or plaits so as to present a substantially plain lower edge portion which is adapted both to snugly receive within its embrace the annular flange of the can bottom and also to be closely embraced throughout its exterior surface by a bottom-retaining chime ring.

In describing the invention in detail, reference is herein had to the accompanying drawings, in which—

Figure 1 is a side elevation of the invention;

Figure 2 is an enlarged elevation of a fragmentary portion of the lower end of the can;

Figures 3 and 4 are vertical sections taken on lines 3—3 and 4—4, respectively, of Fig. 1; and—

Figure 5 is a horizontal section on line 5—5, Fig. 1.

Referring to said drawings, 1 indicates generally the can body which is formed of a single rectangular sheet of metal. Said body is corrugated vertically from its upper end, or from a point slightly below the usual reinforcing ring 2 provided in the mouth of said body, to its lower end. The

corrugations gradually increase in depth and correspondingly decrease in width from their upper ends downward to provide for absorption of the metal to the extent that a gradual but decided taper, or reduction in the diameter, of the can body is produced as the bottom of the body is approached.

To provide for close seating within the lower edge portion of the can body of the downwardly directed annular flange 3 of a bottom 4, the corrugations of said portion are flattened out, such flattening being effected by laying over the surplus or excess metal in folds or plaits 5, as is best shown in Fig. 5. Internal and external shoulders 6 and 7 are formed at suitable points in the plaited lower edge portion of the body preferably by pressing in said edge an internal annular bead 8. The internal shoulder 6 constitutes a rest against which the bottom 4 seats and whereby said bottom is prevented from being forced upward out of place.

Disposed in clamping relation to the lower plaited edge of the can body and the flange 3 of the bottom 4 is a chime ring 9 by which said parts are securely maintained in proper relation and also whereby suitable reinforcement is afforded for the lower part of the can. Said ring has its inner edge portion 9^a disposed vertically against the inner face of the bottom flange 3, thence extends outward in underlying relation to the extreme lower edges of said flange and the can body, and thence extends upward against the outer face of the plaited edge portion of said body and has its opposite, or outer, edge turned inward and seated in overlying relation to the shoulder 7.

At a point slightly above the bead 8 each of the furrows of the corrugations is pressed or bulged outward a distance approximating one-half its depth to meet the upper part of the indentation made in the production of said bead, as shown at 10. Thus, an approximately flat surface for the laying over of the folds or plaits is produced.

What is claimed is—

1. A sheet-metal can of the character described comprising a downwardly tapered body having vertical corrugations which increase in depth and decrease in width toward its lower end whereby reduction in diameter of said body is effected, said cor-

ruggations being terminated above the lower edge of said body, the uncorrugated lower edge portion having the surplus metal thereof laid over in flattened plait-like folds and being flexed at a suitable point in internal bead form to provide an internal downwardly facing shoulder and an external upwardly facing shoulder, a bottom fitted in underlying seated relation to the internal shoulder, and a reinforcing chime ring disposed in supporting relation to said bottom, said ring embracing said edge portion below said bead and having its outer edge turned inward into overlying relation to the external shoulder:

2. A sheet-metal can of the character described comprising a downwardly tapered body having vertical corrugations which increase in depth and decrease in width toward its lower end whereby reduction in diameter of said body is effected, said corrugations being terminated above the lower

edge of said body, the uncorrugated lower edge portion having the surplus metal thereof laid over in flattened plait-like folds and being flexed at a suitable point in internal bead form to provide an internal downwardly facing shoulder and an external upwardly facing shoulder, a bottom fitted in underlying seated relation to the internal shoulder, said bottom having a depending peripheral flange seated against said lower edge portion, and a chime ring disposed in embracing relation to said edge portion and said flange and having its outer edge seated upon the external shoulder.

In testimony whereof, I affix my signature in presence of two subscribing witnesses.

HENRY KIELBERG.
